RETRACTABLE DRILL COLLAR STABILIZER
Jackson M. Kellner, Tulsa, Okla., assignor to ESSO Pro-
duction Research Company, a corporation of Dela-
ware

Filed Feb. 9, 1960, Ser. No. 7,671
8 Claims. (Cl. 166—237)

The present invention relates to apparatus useful for drilling boreholes in the earth and more particularly relates to an improved drill collar stabilizer for use in the rotary drilling of such boreholes. In still greater particularity, the invention relates to a retractable, hydraulically-actuated drill collar stabilizer free of many of the disadvantages which have limited the application of drill collar stabilizers in the past.

The successful rotary drilling of oil wells, gas wells, and similar boreholes in the earth requires the application of high pressures to the formation beneath the drill bit. For this reason, it is conventional to provide a series of heavy drill collars in the drill string just above the bit. The drill collars thus employed may weigh from 50,000 to 100,000 pounds or more and may extend several hundred feet up the drill string. The weight of the drill collars supplies the necessary pressure and at the same time holds the drill pipe in the upper part of the hole in tension so that it has little tendency to buckle or flex as it is rotated. The collars themselves, however, are under compression and hence do tend to buckle to some extent. This buckling action, combined with the tendency of dipping, laminated strata to deflect the bit, often leads to the drilling of crooked, sloping boreholes. In such a borehole, the weight of the drill collars below the point of last contact with the borehole wall may be divided into two components: one acting along the axis of the collars and a second acting normal to the first toward the low side of the hole. This second component is generally referred to as the pendulum force. The portion of the drill string above the point of last contact which is not in tension results in an additional force which is transmitted axially by the collars and is in effect applied from the point of contact at an angle greater than the deviation angle. Ignoring effects due to heterogeneity of the rock being drilled, the bit will advance in the direction of the resultant of the pendulum force and the forces transmitted axially by the drill collars. If the angle of the resultant to the vertical exceeds the deviation angle, continued drilling will result in greater deviation; whereas continued drilling will produce a decrease in deviation if the angle of the resultant to the vertical is less than the deviation angle. The angle which the resultant makes with the vertical can be changed by changing the pendulum force, by changing the force transmitted axially by the drill collars, or by changing the direction in which the axially-transmitted force is applied to the bit.

The normal method for correcting deviation is to place a drill collar stabilizer in the drill string at an intermediate point between two drill collar sections in order to hold the drill collars away from the borehole wall. This raises the point of contact between the drill string and wall and thus increases the magnitude of the pendulum force at the bit. It also decreases the angle to the vertical at which the forces transmitted axially by the drill collars are applied to the bit. The more nearly vertical resultant force acting on the bit tends to force it to drill in a more vertical direction. Continued use of a drill collar stabilizer in this manner will in most cases eventually result in straightening of the borehole.

The drill collar stabilizers employed in the manner set forth above are generally tubular members provided with lateral projections which, when the stabilizer is connected between adjacent drill collars, will bear on the sloping

2

borehole wall and hold the collars away from the wall. The outer diameter of such a stabilizer should be slightly smaller than the diameter of the borehole in order to permit continuous downward movement of the drill collar and stabilizer as the drilling operation progresses and yet should be large enough to permit suspension of the drill collars as far from the borehole wall as possible. Stabilizers employed heretofore have generally had fixed projections or ribs made of rubber, steel or a similar material. Experience has shown that stabilizers of this type are not wholly satisfactory because the projections or ribs tend to snag the walls of the borehole during trips to and from the surface. This often results in damage to the walls and in some cases may cause the drill string to become stuck in the borehole. Stabilizers provided with projections which will deflect on contact with the borehole during trips into and out of the borehole have been suggested recently but have been found equally unsatisfactory. It is difficult to make the projections resilient enough to avoid damage to the borehole wall during tripping and yet make them stiff enough to resist the weight of the drill collars against the wall in a sloping borehole. Moreover, resilient projections or ribs of rubber or similar material are frequently cut and abraded upon contact with shales and other hard strata during tripping.

The present invention provides a new and improved drill collar stabilizer having retractable projections or shoes which will effectively support the drill collars for stabilization purposes and yet can easily be withdrawn from the borehole without injuring the shoes or damaging the borehole wall. The improved stabilizer thus provided includes a hollow mandrel having a passage through which drilling fluid can be admitted to an annular sleeve mounted on the mandrel. The sleeve contains a plurality of openings in which are positioned extensible shoes held in place by rubber or similarly elastic collars. Circulation of drilling fluid through the drill string results in a pressure differential across the shoes which forces them outwardly into an extended position. When fluid circulation is interrupted and the pressure equalized, rubber collars surrounding the shoes force them back into the retracted position. The stabilizer thus supports the drill collars away from the borehole wall as long as drilling fluid is being circulated and is automatically retracted for tripping purposes when the fluid pressure is reduced. This permits rapid tripping into and out of the borehole, reduces wear and abrasion of the stabilizer shoes, and decreases the likelihood of damage to the borehole wall during tripping.

The exact nature and objects of the invention can best be understood by referring to the following detailed description of a preferred embodiment of the improved drill collar stabilizer and to the accompanying drawings, in which:

FIG. 1 is an elevational view, partially in section, of a drill collar stabilizer provided with hydraulically-actuated shoes constructed in accordance with the invention;

FIG. 2 is a cross-sectional view through the apparatus of FIG. 1 taken along the line 2—2;

FIG. 3 is a partially-sectioned view of a shoe slightly modified from that shown in FIGS. 1 and 2; and,

FIG. 4 is a small scale elevational view of the lower end of a rotary drill string provided with a drill collar stabilizer for straightening the borehole.

Turning first to FIG. 1 of the drawing, the tool depicted therein includes a mandrel 11 which is generally cylindrical in shape and contains an axial passage 12 through which fluids may flow from one end of the tool to the other. The mandrel is provided with means at its upper and lower ends for connecting the tool at an intermediate position within a conventional rotary drill string. As depicted in the drawing, the mandrel includes a standard

API pin joint 13 at its lower end and a separate API box joint 14 connected to the upper end of the mandrel by threads or equivalent means 15 in order to permit disassembly of the tool when desired. Mandrel 11 is divided axially into three integral sections, a lower section 16 of relatively large diameter located just above pin joint 13, an intermediate section 17 separated from lower section 16 by tapered shoulder 18, and an upper section 19 between box joint 14 and intermediate section 17 which is separated from the intermediate section by a second tapered shoulder 20. Fluid passage 21 extends laterally from axial passage 12 to the outer surface of the mandrel within intermediate section 17. Fluid grooves 22 and 23 are located on the outer surface of the mandrel respectively above and below the outlet of passage 21 for stress relief purposes. The upper end of lower mandrel section 16 is provided with a notched shoulder 24.

Sleeve 25 in FIG. 1 of the drawing is a tubular member carried on intermediate section 17 and upper section 19 of mandrel 11. The sleeve is divided axially by sloping internal shoulder 26 into an upper section 27 and a lower section 28. The inner diameter of integral sleeve sections 27 and 28 are slightly larger than the outer diameters of mandrel section 19 and 17 respectively in order to permit the sleeve to rotate and move axially on the mandrel. Wiper ring 29 and seal ring 30 of rubber or similar elastic material are set in annular grooves on the inner surface of the sleeve near the upper end thereof and provide a fluid-tight seal between the sleeve and mandrel. Passage 31 permits the escape of fluids entrapped between the rings. Similar rings 32 and 33 and passage 34 are located near the bottom of the sleeve for like purposes. As shown, the rings also serve as bearings between the mandrel and sleeve. Separate bearings may be provided if desired. In its lowermost position, the axially slid able sleeve 25 seats upon sloping shoulder 18 on the mandrel and is supported thereby. Box joint 14 extends laterally beyond the mandrel and thus serves to retain the sleeve when it is in its uppermost position. The lower edge of the sleeve is provided with keys 35 so that the mandrel and sleeve may be locked together and rotated in a counterclockwise direction if desired. The faces of the keys are tapered to permit clockwise rotation of the mandrel independently of the sleeve.

Sleeve 25 is provided with a plurality of lateral openings in which the extensible shoes utilized are positioned. It is preferred that the openings be spaced at regular intervals around the sleeve and arranged in a staggered pattern along the vertical axis of the sleeve. Although the stabilizer depicted in the drawing is provided with six extensible shoes, it will be understood that the device is not limited to six shoes and that a greater or lesser number may be utilized.

Positioned in each of the aforementioned lateral openings in sleeve 25 is a supporting ring 36 which is provided with an external shoulder 37. Shoulder 37 mates with a similar shoulder on the wall of the opening and thus serves to retain ring 36 within the opening. The supporting ring is provided with an annular internal shoulder 38 which separates the opening in the ring into an inner section and an outer section of reduced diameter. Shoe 39 having a flange 40 around the back portion thereof is positioned in ring 36 so that the body of the shoe extends into the outer section of the ring opening. Flange 40 on the shoe prevents over-extension by contacting shoulder 38 in the supporting ring. An elastic collar 41 is bonded to the outer surface of the shoe and the inner surface of the supporting ring. The collar may be made of rubber, plastic or similar resilient material. Neoprene and nitrile rubber have been found particularly attractive because of their resistance to deterioration in the presence of crude oils. Collar 41 should be bonded between the ring and shoe in a manner such that the elasticity of the collar tends to hold the shoe in a retracted position within the ring. A material having a sufficient modulus of elasticity to permit extension of the shoe at low differential pres-

sures and capable of withstanding the shear stresses encountered at higher operating pressures should be employed. Good bonding properties to metal are desirable.

As shown more clearly in FIG. 2 of the drawing, the rear surface of shoe 39 is arched and has a radius essentially the same as the inner radius of sleeve 25. In like manner, supporting ring 36 conforms to the inner wall of the sleeve. When the apparatus is assembled as shown in the drawing, mandrel 11 prevents movement of the ring with respect to the sleeve and retains the shoe within the ring. The diameter of the stabilizer with the shoes extended should be slightly less than the diameter of the bit with which the stabilizer is to be used.

FIG. 3 of the drawing depicts a preferred shoe embodiment in which the outer surface of the shoe is provided with a hard surface 42 which extends beyond the edge of the shoe to form a lip 43. This lip protects the bond between shoe 39 and collar 41 and prevents failure of the bond due to wear and abrasion. The elastic collar, in the embodiment shown in FIG. 3, is provided with a lip 44 which covers shoulder 38 in supporting ring 36 and thus assures a fluid-tight seal between the shoe and ring. Such a seal prevents excessive pressure differentials across the collar and permits the use of operating pressures which might not otherwise be feasible. A separate sealing ring of rubber or other material may be provided to effect a seal between the shoulder and flange if desired.

The operation of the improved drill collar stabilizer of the invention for straightening a crooked borehole can best be seen by referring to FIG. 4 of the drawing. After it has become apparent that the bore hole has deviated from the vertical during the drilling operation, the drill string is withdrawn from the hole. The hole is then surveyed to determine the points at which it changes in slope. Conventional inclinometers and similar instruments can be employed for this purpose. The information thus obtained, coupled with information as to the tendency of the drill collars to sag under their own weight, will permit calculation of the distance above the bit at which the stabilizer should be placed in order to suspend the maximum length of drill collars between the bit and stabilizer out of contact with the borehole wall. Standard tables giving these distances for various drill collar and bit sizes and various deflection angles are available and will be familiar to those skilled in the art. The tables also generally indicate the extent to which the weight on the bit can be increased without increasing deviation if a stabilizer is used. The stabilizer is then inserted at the proper place in the drill string and the string is lowered back into the borehole.

After the drill string containing the stabilizer has been lowered in place in the borehole, drilling fluid is circulated downwardly through the string and up the annulus. Fluid flowing through mandrel 11 of the stabilizer enters passage 21 and the space between the outer surface of the mandrel and the sleeve. Pressure behind the stabilizer shoes is therefore essentially the same as that within the mandrel. The pressure on the face of the shoes outside the sleeve, on the other hand, will be considerably less due to the pressure drop across the nozzles of the bit. In response to this difference in pressure, the shoes are forced outwardly until flange 40 contacts shoulder 38 on the retaining ring 36. Extension of the shoes in this manner forces the stabilizer away from the borehole walls so that the lower portion of the drill string is suspended between the stabilizer and bit as shown in FIG. 4 of the drawing. The last point of contact between the drill string and borehole wall is thus higher than it would be in the absence of the stabilizer. This increases the pendulum force on the bit and decreases the angle to the vertical at which forces are transmitted axially by the drill collars to the bit. As a result, the angle of the resultant force to the vertical is reduced.

On resuming rotation of the drill string after the stabilizer has been placed in the borehole as described above, the stabilizer mandrel rotates within the sleeve. The

change in the forces acting on the bit due to the presence of the stabilizer causes the bit to drill in a more nearly vertical direction. As drilling progresses and the drill string moves downwardly, pressure exerted on the sleeve by the lower end of the box joint connected to the upper end of the mandrel forces the sleeve downwardly. The shoes in contact with the borehole walls slide against the wall. Wear on the outer surface of the shoes is generally insignificant because of the slow relative motion between the shoes and the wall and because of the absence of high contact pressures between the shoe and the wall. The outer surfaces of the shoe and collar may, however, be sheathed with an abrasion-resistant material as pointed out heretofore.

Continued drilling of the borehole with the stabilizer in place will normally result in a continuous decrease in the inclination of the hole until it is substantially vertical and the stabilizer shoes no longer bear on the borehole wall. Drilling with the stabilizer in place after the borehole has been straightened has no adverse effect and hence immediate removal of the stabilizer is unnecessary. In many operations wherein it is known that borehole deflection is likely to occur, it is often preferred to drill the entire borehole using the stabilizer placed near the upper end of the drill collar section. When thus used, the stabilizer will begin to correct or control deviations in the borehole before they might otherwise be detected. Repeated surveying of the hole can sometimes thus be avoided.

When the circulation of drilling fluid through the drill string is halted in order to permit withdrawal of the drill string from the borehole, the pressure on the inside and outside surfaces of the shoes equalize. The shoes are thereupon retracted by the elastic collar which connects the shoes and retaining rings in the sleeve. The drill string thereafter can be pulled out of the borehole without danger of injuring the stabilizer shoes or damaging the borehole walls. It is preferred that the shoes in the retracted position in the supporting rings on the sleeves extend slightly beyond the outer surface of the sleeve as shown in the drawing in order to avoid sticking of the sleeve in the borehole due to the "differential effect" sometimes observed when smooth columns contact the borehole walls. An advantage of the hydraulically-actuated shoes employed in the stabilizer of the invention is that the shoes may be extended to free the drill string should it become stuck during tripping. Pressure drop across the nozzles of the bit under full fluid pressure permits extension of the shoes regardless of the position of the drill string in the borehole.

The retractable drill collar stabilizer of the invention may be operated over a wide range of fluid pressures. It is generally preferred that flange 40 on the rear surface of each shoe mate with shoulder 38 on the corresponding supporting ring to form a fluid-tight seal where very high fluid pressures are to be used. This restricts the pressure applied to the elastic collar to that amount necessary to overcome the resistance of the collar and move the shoe outwardly against the shoulder. Fluid pressures well in excess of those at which the collar would otherwise fail or be torn loose from the shoe or ring can thus be safely used.

In the event that the stabilizer should for some reason become stuck in the borehole so firmly that it cannot be extricated by extension of the shoes, it can be removed by lowering a washover device over it and milling off the projection on the surface of the sleeve. Notches on the upper edge of the section of the mandrel and the keys on the lower edge of the sleeve will lock together and prevent the sleeve from rotating on the mandrel as the projections are milled. The shoes and retaining rings can be replaced following such an operation without the necessity for replacing the sleeve and mandrel and hence the damage to the stabilizer is minimized. Because of the very large forces which can be exerted against the borehole wall by

extending the shoes when the drill string becomes stuck in the borehole, the necessity for carrying out such washover operations rarely arises.

What is claimed is:

1. Rotary drilling apparatus which comprises: a mandrel provided with means at its upper and lower ends for connecting said apparatus at an intermediate point in a rotary drill string, said mandrel including a longitudinal passageway for the transmission of drilling fluid and a lateral passageway extending through the mandrel wall from said longitudinal passageway to a port in the outer surface of said mandrel;

a tubular sleeve slidably mounted on said mandrel over said port for longitudinal and rotational movement thereon, said sleeve containing a plurality of vertically and circumferentially spaced wall openings to permit the centering of said sleeve and mandrel in the borehole by shoes mounted in said openings;

a plurality of laterally-extensible shoes positioned in said wall openings in said sleeve;

an elastic member bonded to said shoe within each of said wall openings and connected to the surrounding sleeve, said elastic member forming a fluid-tight seal about said shoe and biasing said shoe in a normally retracted position with respect to said sleeve while permitting extension of said shoe in response to fluid pressure between said sleeve and mandrel; means for limiting the extension of said shoes and thereby preventing the anchoring of said apparatus in said borehole;

upper and lower seal members positioned between said sleeve and mandrel respectively above and below said wall openings;

and means limiting longitudinal movement of said sleeve with respect to said mandrel.

2. Rotary drilling apparatus which comprises:

a tubular mandrel provided with means near the upper and lower ends thereof for connecting said mandrel at an intermediate point in a rotary string, said mandrel including a passageway extending through the mandrel wall to a port in the outer surface thereof;

a tubular sleeve slidably mounted on said mandrel over said port for longitudinal and rotational movement thereon, said sleeve containing a plurality of wall openings vertically and circumferentially spaced to permit centering of the sleeve and mandrel in a borehole by means of shoes mounted in said openings;

a supporting ring seated in each of said wall openings in fluid-tight relationship to said sleeve;

a laterally-extensible shoe positioned within each of said supporting rings;

an elastic member bonded to said shoe and to said supporting ring in each of said wall openings to form a fluid-tight seal, said elastic member biasing said shoe in a normally retracted position with respect to said sleeve while permitting extension of said shoe in response to fluid pressure between said sleeve and mandrel;

means for limiting the extension of said shoes with respect to said sleeve and thereby preventing the anchoring of said apparatus in said borehole;

upper and lower seal members positioned between said sleeve and mandrel respectively above and below said wall openings;

and means for limiting longitudinal movement of said sleeve with respect to said mandrel.

3. A drill collar stabilizer comprising:

an elongated tubular mandrel provided with means for connecting said mandrel at an intermediate point in a rotary drill string, said mandrel including an intermediate section of reduced diameter and a lateral passageway extending through the mandrel wall within said intermediate section;

a longitudinally-extending sleeve mounted on said intermediate section of said mandrel for longitudinal and rotational movement thereon, said sleeve containing a plurality of wall openings vertically and circumferentially spaced to permit centering of the sleeve and mandrel in a borehole by means of shoes mounted in said openings; 5
 a supporting ring mounted in each of said wall openings in fluid-tight relationship to said sleeve, each of said supporting rings containing an internal shoulder located near the outer face of said ring; 10
 a laterally-extensible shoe mounted in each of said supporting rings, each of said shoes including a section having an outer diameter greater than the inner diameter of said shoulder on said ring; 15
 an elastic member bonded to the outer periphery of said shoe and the inner periphery of said ring within each of said wall openings to form a fluid-tight seal, said elastic member biasing said shoe in a normally retracted position with respect to said ring while permitting extension of said shoe with respect to said ring in response to fluid pressure between said sleeve and mandrel; 20
 and upper and lower seal members positioned between said sleeve and mandrel respectively above and below said wall openings. 25
 4. A drill collar stabilizer which comprises:
 an elongated tubular mandrel provided with means near the upper and lower ends thereof for connecting said mandrel at an intermediate position within a rotary drill string, said mandrel including an intermediate section of reduced diameter and a lateral passageway extending through the mandrel wall within said intermediate section; 30
 a longitudinally-extending sleeve slidably mounted on said intermediate section of said mandrel for longitudinal and rotational movement thereon, said sleeve containing a plurality of wall openings vertically staggered and spaced at circumferential intervals about the sleeve to permit centering of the sleeve and mandrel in a borehole by means of shoes mounted in said openings; 35
 a supporting ring mounted in each of said wall openings in fluid-tight relationship to said sleeve, each of said supporting rings containing an internal shoulder located near the outer face of said ring; 40
 a laterally-extensible shoe positioned within each of said supporting rings, each of said shoes including a rear flange having an outer diameter greater than the inner diameter of said shoulder on said ring; 45
 an elastic sleeve bonded to the outer periphery of said shoe and the inner periphery of said ring in each of said wall openings to form a fluid-tight seal, said elastic member biasing said shoe in a normally retracted position with respect to said ring while permitting extension of said shoe with respect to said ring in response to fluid pressure between said sleeve and mandrel; 50
 and upper and lower seal members positioned between said sleeve and mandrel respectively above and below said wall openings in said sleeve. 60
 5. A drill collar stabilizer comprising:
 an elongated tubular mandrel provided with means for connecting said mandrel at an intermediate point within a rotary drill string, said mandrel including an intermediate section of reduced diameter and a lateral passageway extending through the mandrel wall within said intermediate section; 65
 a longitudinally-extending sleeve mounted on said intermediate section of said mandrel for longitudinal and rotational movement thereon, said sleeve containing a plurality of wall openings vertically staggered and equally spaced circumferentially whereby said sleeve

and mandrel are centered in the borehole by shoes mounted in said openings; 8
 a laterally-extensible shoe mounted in each of said wall openings; 5
 an elastic member bonded to each of said shoes and connected to the surrounding sleeve to form a fluid-tight seal within each of said wall openings, said elastic member biasing said shoe in a normally retracted position with respect to said sleeve while permitting extension of said shoe in response to fluid pressure between said sleeve and mandrel; 10
 means associated with said shoe and sleeve for limiting the extension of said shoes and thereby preventing the anchoring of said stabilizer in said borehole; 15
 upper and lower seal members positioned between said sleeve and mandrel respectively above and below said wall openings; 20
 means for limiting longitudinal movement of said sleeve on said mandrel; 25
 and means for interlocking said sleeve and mandrel to prevent clockwise rotation of said sleeve with respect to said mandrel when said sleeve is in the lowermost position on said mandrel. 30
 6. A shoe assembly for use on a down-hole tool containing a lateral opening in which a hydraulically extensible shoe is positioned which comprises:
 a supporting ring for retention in said opening, said ring having an outer section and an inner section of enlarged diameter separated from said outer section by an internal shoulder; 35
 a shoe mounted within said ring and provided with a rear section for engaging said shoulder in said ring; and an elastic collar bonded to said ring and said shoe for retaining said shoe in a normally retracted position with respect to said ring while permitting extension of said shoe in response to fluid pressure from within said ring. 40
 7. An assembly as defined by claim 6 wherein said elastic member extends over said shoulder in said ring to effect a seal between said shoulder and said rear section on said shoe when the shoe is in its outermost position with respect to said ring. 45
 8. A shoe assembly for use on a down-hole tool containing a lateral opening in which a hydraulically extensible shoe is positioned which comprises:
 a supporting ring for retention in said opening; 50
 a shoe mounted within said supporting ring; 55
 an elastic collar bonded to the inner surface of said supporting ring and the outer surface of said shoe for retaining said shoe in a normally retracted position with respect to said ring while permitting extension of said shoe relative to said ring in response to fluid pressure; 60
 and means independent of fluid pressure for preventing the extension of said shoe with respect to said ring beyond a predetermined point. 65
